[57] **CLAIM**

The ornamental design for a golf club head, substantially as shown and described.

DESCRIPTION

FIG. 1 is a rear elevation of a golf club head embodying my new design;

FIG. 2 is a front elevation of the golf club head shown in FIG. 1;

FIG. 3 is a toe-end elevation of the golf club head shown in FIG. 1;

FIG. 4 is a sectional view of the golf club head shown in FIG. 1 taken along a line 4—4.

My new design may be applied to golf club heads that have a different loft and lie in a conventional manner.
